Primary Examiner — Elizabeth J Oswecki*(74) Attorney, Agent, or Firm* — Fitch, Even, Tabin & Flannery(57) **CLAIM**

The ornamental design for a bottle, as shown and described.

DESCRIPTION

FIG. 1 is a top, front, right side, perspective view of a bottle showing our new design;

FIG. 2 is a front elevation view thereof, the rear elevation view being identical thereto;

FIG. 3 is a side elevation view thereof, the opposite side being identical thereto;

FIG. 4 is a top plan view thereof; and,

FIG. 5 is a bottom plan view thereof.

The broken lines shown in the drawings are for illustrative purposes only and form no part of the claimed design.
